UNITED STATES PATENT OFFICE

149,204

DESIGN FOR A CHILD'S FOLDABLE TOILET SEAT

Leonard C. Neufeld, Des Moines, Iowa, assignor to Fol-Dee Seat Company, Des Moines, Iowa, a corporation of Iowa

Application December 26, 1946, Serial No. 135,775

Term of patent 14 years

(Cl. D4—5)

To all whom it may concern:

Be it known that I, Leonard C. Neufeld, a citizen of the United States, and a resident of Des Moines, in the county of Polk and State of Iowa, have invented a new, original, and ornamental Design for a Child's Foldable Toilet Seat, of which the following is a specification, reference being had to the accompanying drawing forming part hereof, in which:

Fig. 1 is a plan view of a child's foldable seat showing my new design;

Fig. 2 is a side elevational view as seen looking in an upward direction relative to Fig. 1;

Fig. 3 is a front view looking toward the right in Fig. 1;

Fig. 4 is a bottom view;

Fig. 5 is a rear view looking toward the left in Fig. 1;

Fig. 6 is a rear view of a half portion of the seat with the rear part of a supporting arm broken away; and

Fig. 7 is a side elevational view showing the seat in a folded position.

The dominant features of my design are illustrated in full lines in the drawings.

I claim:

The ornamental design for a child's foldable toilet seat, substantially as shown and described.

LEONARD C. NEUFELD.
